(57) CLAIM

The ornamental design for a novelty sign, as shown and described.

DESCRIPTION

FIG. 1 is a top view of a novelty sign in accordance with the present invention;

FIG. 2 is a front view of the novelty sign;

FIG. 3 is a first side view of the novelty sign;

FIG. 4 is a rear view of the novelty sign;

FIG. 5 is a second side view of the novelty sign; and,

FIG. 6 is a bottom view of the novelty sign.

The broken lines in the drawings represent environmental structure only and form no part of the claimed design.
